UNITED STATES PATENT OFFICE.

RALPH K. THOMSON, OF SIOUX FALLS, SOUTH DAKOTA.

DESIGN FOR A SIDE CURTAIN FOR AUTOMOBILES.

57,285.

Specification for Design.

Patented Mar. 8, 1921.

Application filed June 28, 1920. Serial No. 392,530. Term of patent 14 years.

To all whom it may concern:

Be it known that I, RALPH K. THOMSON, a citizen of the United States, residing at Sioux Falls, in the county of Minnehaha and State of South Dakota, have invented a new, original, and ornamental Design for Side Curtains for Automobiles, of which the following is a specification, reference being had to the accompanying drawing, forming part thereof.

The figure is a plan view of the curtain for use as an automobile side curtain showing my new design.

I claim:

The ornamental design for a side curtain for automobiles, as shown.

RALPH K. THOMSON.
